RAZOR BLADE HOLDER

Carlyle B. Stair, Glendale, Calif.

Application August 20, 1949, Serial No. 111,352

10 Claims. (Cl. 30—162)

1

This invention relates to a holder for razor blades to enable the blade to be used for various cutting and scraping operations, and particularly to a form thereof in which the blade is held normally retracted and can be readily moved out of the protecting portions of the holder incident to use.

The principal object of the invention is to provide a holder for safety razor blades including spring means operable normally to retract the blade, and which, upon applying pressure incident to the normal manner of gripping the holder for use, will operate to move the edge of the blade out of the holder.

Another object of the invention is to provide a holder for razor blades of the above character including means whereby the blade may be locked in exposed or operative position.

Still another object of the invention is to provide a holder for safety razor blades having capacity to retract and expose the edge of the blade at the will of the user in which a single manually operable element serves both to move the blade into exposed position and, optionally, to lock the blade in exposed position.

A further object of the invention is to provide a razor blade holder in which the blade is normally retracted by spring means and in which the blades are inserted through a slot in one end of the holder; the insertion of one blade serving to eject the blade in the holder.

A still further object of the invention is to provide a razor blade holder having the above desirable characteristics which is composed of few parts of simple design, which is economical to manufacture, attractive in appearance and both reliable and safe in use.

With the above objects in view, together with such other objects and advantages as may subsequently appear, the invention resides in the parts, and in the construction, combination, and arrangement of parts, described in the following specification and illustrated in the accompanying drawings which form a part of said specification showing by way of example, one mode of execution of the invention and in which:

Fig. 1 is a front elevation of a razor blade holder embodying the invention,

Fig. 2 is an end elevation of Fig. 1,

Fig. 3 is a rear elevation of the holder shown in Fig. 1; the edge of a blade carried thereby being moved to exposed position and a portion of the case being broken away to show details of interior construction,

2

Fig. 4 is a side elevation of the interior face of the rear case member,

Fig. 5 is an elevation of the inner face of the front case member,

5 Figs. 6, 7 and 8 are front end and rear elevations, respectively, of the blade manipulating element,

Figs. 9 and 10 are transverse sectional views taken on the line 9—9 of Fig. 1 showing the relative positions of the case, the blade and the blade manipulating elements as the blade is retracted or exposed, respectively, and

Figs. 11, 12 and 13 are vertical sectional views taken on the lines 11—11 of Figs. 3 and 9 showing the relative positions of the case and the blade manipulating element when the blade is retracted, exposed, and locked in exposed position, respectively.

The case of the device comprises a front member 1 having a rectangular opening 2 in the side face thereof, and on its inner face having a longitudinal slot 3 adapted to receive a tongue 4 on the inner face of the rear member 5. Additionally, the member 1 is provided with a pair of dowel pins 6, 6 which engage corresponding holes 7, 7 in the member 1. The upper ends of both members meet along the center line 8 of the case and are preferably cemented together. At about their midpoints, the inner faces of the members 1 and 5 are provided with shallow, opposed longitudinal grooves 9 and 10 which combine to form a slot 10' sufficiently large to receive the reinforced head H of a single edge razor blade B. Below the grooves 9 and 10, the inner faces of the members 1 and 5 are spaced apart slightly more than the thickness of a razor blade. Thus, the case has openings extending from end to end thereof through which razor blades may be passed, as will be later explained.

Disposed on the inner face of the member 5 adjacent the upper edge of the slot 10 is a rectangular recess 11 and adjacent the lower edge thereof, the inner face of the member 5 is a second rectangular recess 12 adapted to receive a double ended leaf spring 13, which is somewhat wider than the depth of the recess 12 (see Figs. 9 and 10) and the upper inturned ends of which spring are engaged by the lower edge of the head H of the razor blade as shown in Fig. 9 or 10. The action of the ends of the springs tends constantly to urge the blade upwardly into the case to the extent permitted by the upper edge of the slot 12.

The member 1 on its inner face is provided 55 with a large rectangular recess 14 which is in-

tersected at about its midpoint by the rectangular opening 2 (see Fig. 5). At its upper edge, locking lugs 15 and 16 formed as integral portions of the member 1 project downwardly into the recess 14.

The blade manipulating element 17 includes a rectangular portion 18 which projects through the opening 2 in the case member 1 and this portion is somewhat smaller than the opening 2 so that it may move both vertically and endwise therein. On its opposite face the element 17 is provided with a V-shaped, longitudinally extending lug 19 adapted to enter the rectangular recess 11. The upper cam face 20 of the lug 19 engages the upper corner 21 of the recess 11 15 and the lower face 22 engages the upper edge of the head H of the razor blade. The element 17 also includes a depending narrow flange 23, which is disposed in the lower portion of the recess 14 and which serves as a fulcrum point for the movement of the element incident to its movement with the razor blade. At its upper end, the element 17 is provided with spaced, upwardly extending flange portions 24 and 25 adapted normally to fit into the spaces 26 and 27 adjacent the locking lugs 15 and 16.

When the device is not being used, the spring 13 will press the razor blade upwardly and the upper end of the head of the blade engaging the came face 22 of the member 17 co-acting with the corner 21 will tend to move the member 17 upwardly and to the left as shown in Fig. 9. When the member 17 is moved inwardly by pressure on the portion 18 thereof, the wedging action of the cam member 19 will move both the member 17 and the razor blade downwardly as shown in Fig. 10 exposing the edge of the blade through the slot 28, extending along the lower end of the case. This movement will bring the flanges 24 and 25 clear of the members 15 and 16 as shown in Fig. 12, and, since the member 18 is of less length than the opening 2, it can be moved to the left as viewed in Fig. 1 or to the right as viewed in Fig. 2, bringing the flanges 24 and 25 opposite the locking lugs 15 and 16, respectively, as shown in Fig. 13, thus locking the member 17 in its inward position and consequently, locking the blade with the edge thereof exposed. Upon moving the element 17 endwise of the case in the opposite direction, the action of the spring will be free to move the blade upwardly with incident outward movement of the member 17.

To insert a blade in the device, it is necessary merely to move the blade endwise with the head thereof entering the slot formed by the opposed grooves 9 and 10 and the under edge of the head of one side of the blade will ride over the ends of the spring 13. When a new blade is to be inserted, such endwise insertion will operate simultaneously to push out the blade to be removed from the opposite end of the device.

While the above described form of the invention is adapted for a specific type of razor blade, of which there are several forms on the market, it will be appreciated that the principles of the device can be adapted to other forms of blades without departure from the invention.

All of the parts are of simple design, and are not of great depth so that the making of molds to produce these parts in plastic is not expensive. The only metal part, aside from the razor blade, is the spring element and this too is of very simple design. The device is safe to use in that whenever it is not in use, the blade is retracted

5 into the case and therefore the device is safe to handle. At the same time, the device is large enough to permit it to be readily grasped in the hand for such operation as scraping paint, ripping seams, making erasures, and all of the other uses to which razor blades are put.

While in the foregoing specifications and drawings, I have disclosed one embodiment of my invention, I do not intend thereby to limit myself to the exact form there disclosed, and the invention includes all such modifications in the parts, and in the construction, combination and arrangement of parts, as shall come within the purview of the appended claims.

I claim:

1. A holder for safety razor blades adapted to enable such blades to be used for scraping and cutting uses comprising a case formed of mating halves, the interiors of which combine to form a blade receiving cavity therein and having slots at each end to permit the insertion and removal of blades, spring means in said case operative to maintain a blade retracted and a manually operable element disposed in said cavity and having a portion thereof protruding through an opening in said case operable to cause the edge of a blade contained in said case to be projected beyond said case.

2. A holder for safety razor blades adapted to enable such blades to be used for scraping and cutting uses comprising a case formed of a pair of generally rectangular members secured together along one side edge and part of the adjacent end edges and having the adjacent faces thereof along the other side edge and the rest of said end edges spaced apart to form a blade receiving slot, spring means in said casing constructed and arranged to normally maintain a blade in said case retracted, and a member in said case having a manually engageable surface extending through an opening in said case, operable to move said blade against said spring means so that the edge thereof is moved through said slot and exposed for use.

3. A holder for safety razor blades adapted to enable such blades to be used for scraping and cutting uses comprising a case formed of a pair of generally rectangular members secured together along one side edge and part of the adjacent end edges and having the adjacent faces thereof along the other side edge and the rest of said end edges spaced apart to form a blade receiving slot, spring means in said casing constructed and arranged to normally maintain a blade in said case retracted, and a member in said case having a manually engageable surface extending through an opening in said case operable to move said blade against said spring means so that the edge thereof is moved through said slot and exposed for use; said member and said case having interengaging portions effective to lock the blade in exposed position.

4. A holder for safety razor blades adapted to enable such blades to be used for scraping and cutting uses comprising a case formed of mating halves, the interiors of which combine to form a blade receiving cavity therein and having slots at each end to permit the insertion and removal of blades, spring means in said case operative to maintain a blade retracted and a manually operable element disposed in said cavity and having a portion thereof protruding through an opening in said case operable to cause the edge of a blade contained in said case to be projected beyond said case; said element being operable in one direc-

tion to project the edge of the blade beyond said case and movable in another direction to lock the edge of the blade in said projected position.

5. A holder for safety razor blades adapted to enable such blades to be used for scraping and cutting uses comprising a case of generally rectangular side outline having an internal cavity and a blade receiving slot communicating with said cavity; said slot extending along one side edge of said case and part way along the portions of both end edges adjacent said side edge, an opening in one side wall of said case communicating with said cavity, a cam face on the side of said cavity remote from said side wall, a blade operating element in said cavity having a manually engageable portion projecting through said opening and having a cam face engageable with said first named cam face; said cam faces being so disposed that upon movement of said element by pressure on said manually engageable portion said element will be moved bodily to cause the edge of a blade carried in said case to be projected through said slot.

6. A holder for safety razor blades adapted to enable such blades to be used for scraping and cutting uses comprising a case of generally rectangular side outline having an internal cavity and a blade receiving slot communicating with said cavity; said slot extending along one side edge of said case and part way along the portions of both end edges adjacent said side edge, an opening in one side wall of said case communicating with said cavity, a cam face on the side of said cavity remote from said side wall, a blade operating element in said cavity having a manually engageable portion projecting through said opening and having a cam face engageable with said first named cam face; said cam faces being so disposed that upon movement of said element by pressure on said manually engageable portion, said element will be moved bodily to cause the edge of a blade carried in said case to be projected through said slot, a spring in said cavity, operable to engage a blade carried in said case and to maintain the blade in engagement with said element.

7. A holder for safety razor blades adapted to enable such blades to be used for scraping and cutting uses comprising a case of generally rectangular side outline having an internal cavity and a blade receiving slot communicating with said cavity; said slot extending along one side edge of said case and part way along the portions of both end edges adjacent said side edge, an opening in one side wall of said case communicating with said cavity, a cam face on the side of said cavity remote from said side wall, a blade operating element in said cavity having a manually engageable portion projecting through said opening and having one cam face engageable with said first named cam face and a second cam face engageable with a razor blade in said case, and a spring mounted in said cavity and operable to maintain a razor blade carried by said case in engagement with said second cam face.

8. A holder for safety razor blades adapted to enable such blades to be used for scraping and cutting uses comprising a case of generally rectangular side outline having an internal cavity and a blade receiving slot communicating with

said cavity; said slot extending along one side edge of said case and part way along the portions of both end edges adjacent said side edge, an opening in one side wall of said case communicating with said cavity, a cam face on the side of said cavity remote from said side wall, a blade operating element in said cavity having a manually engageable portion projecting through said opening and having one cam face engageable with said first named cam face and a second cam face engageable with a razor blade in said case, and a spring mounted in said cavity and operable to maintain a razor blade carried by said case in engagement with said second cam face; said cam faces being operative upon manual pressure applied to said element to cause the edge of the blade to be projected through said slot.

9. A holder for safety razor blades adapted to enable such blades to be used for scraping and cutting uses comprising a case of generally rectangular side outline having an internal cavity and a blade receiving slot communicating with said cavity; said slot extending along one side edge of said case and part way along the portions of both end edges adjacent said side edge, an opening in one side wall of said case communicating with said cavity, a cam face on the side of said cavity remote from said side wall, a blade operating element in said cavity having a manually engageable portion projecting through said opening and having a cam face engageable with said first named cam face; said cam faces being so disposed that upon movement of said element by pressure on said manually engageable portion, said element will be moved bodily to cause the edge of a blade carried in said case to be projected through said slot, a spring in said cavity, operable to engage a blade carried in said case and to maintain the blade in engagement with said element; said element and said case having interengaging portions operable to lock the blade in projected position.

10. A holder for safety razor blades adapted to enable such blades to be used for scraping and cutting uses comprising a case of generally rectangular side outline having an internal cavity and a blade receiving slot communicating with said cavity; said slot extending along one side edge of said case and part way along the portions of both end edges adjacent said side edge, an opening in one side wall of said case communicating with said cavity, a cam face on the side of said cavity remote from said side wall, a blade operating element in said cavity having a manually engageable portion projecting through said opening and having one cam face engageable with said first named cam face and a second cam face engageable with a razor blade in said case, and a spring mounted in said cavity and operable to maintain a razor blade carried by said case in engagement with said second cam face; said cam faces being operative upon manual pressure applied to said element to cause the edge of the blade to be projected through said slot; said element and said case having interengaging portions operable to lock the blade in projected position.
